Fig. 4

Fig. 3

Fig.5

FIG. 1 is a rear elevational view of a camping trailer showing our new design;

FIG. 2 is a top plan view thereof;

FIG. 3 is a side elevational view thereof;

FIG. 4 is a side elevational view thereof opposite to that shown in FIG. 3; and

FIG. 5 is a front elevational view thereof.

The fragmentary criss-cross pattern shown within the substantially rectangular areas in FIGS. 1 and 5 is representative of screening and is understood to be continuous throughout said rectangular areas.

We claim:

The ornamental design for a camping trailer, as shown and described.
